UNITED STATES PATENT OFFICE.

GEORGE CHRISTENSEN, OF LOS ANGELES, CALIFORNIA.

DESIGN FOR AN EMBLEM.

50,932.

Specification for Design. Patented June 19, 1917.

Application filed April 17, 1917. Serial No. 162,769. Term of patent 3½ years.

To all whom it may concern:

Be it known that I, GEORGE CHRISTENSEN, a citizen of the United States, residing at Los Angeles, in the county of Los Angeles, State of California, have invented a new, original, and ornamental Design for Emblems, of which the following is a specification, reference being had to the accompanying drawings, forming a part thereof.

I claim:

The ornamental design for an emblem as shown.

GEO. CHRISTENSEN.
